Limited, Weston, Ontario, Canada, a corporation of Canada

Filed Jan. 27, 1964, Ser. No. 78,385

Term of patent 7 years

(Cl. D81—26)

The figure is a perspective view of a combined oven and control panel for an electric range showing my new design.

The rear of the combined oven and control panel is flat and plain and the side not shown is substantially a mirror image of the side shown.

I claim:

The ornamental design for a combined oven and control panel for electric range, as shown and described.
